(57) **CLAIM**

The ornamental design for a beverage dispensing bladder, as shown and described.

DESCRIPTION

FIG. 1 is an exploded top front perspective view of a beverage dispensing bladder in its empty condition showing our new design;

FIG. 2 is an exploded front view thereof;

FIG. 3 is an exploded rear view thereof;

FIG. 4 is an exploded left side view thereof;

FIG. 5 is an exploded right side view thereof;

FIG. 6 is an exploded top view thereof; and

FIG. 7 is an exploded bottom view thereof.

FIG. 8 is a top front perspective view of a beverage dispensing bladder in its partially full condition;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.
